UNITED STATES PATENT OFFICE.

THOMAS APPLEBY, OF PHILADELPHIA, PENNSYLVANIA, ASSIGNOR OF ONE-THIRD
TO CORNELIUS D. EHRET, OF PHILADELPHIA, PENNSYLVANIA.

CONTROL METHOD AND APPARATUS.

Application filed July 6, 1921. Serial No. 482,827.

My invention relates to a method of and apparatus for controlling thermionic or electron discharge apparatus utilizable in any suitable relation, including radio telegraphy, telephony or other signaling and systems wherein a conductor or conductors extend between transmitting and receiving stations.

In accordance with my invention, the potential of the grid or control electrode of a thermionic or electron discharge device is suitably controlled, as by being made or held to suitable extent negative, without recourse to a battery for such purpose as heretofore commonly practiced, but by suitably connecting the grid or control electrode with another thermionic or electron discharge device and its associated circuit or circuits.

More particularly, in accordance with my invention, the grid is biased as to its potential by recourse to a connection to a suitable point in the grid leak circuit or path of another thermionic or electron discharge device, which latter may be employed in the production of oscillations, such as high frequency oscillations.

In accordance with my invention, the device whose grid potential is so biased may be employed for any suitable purpose, as, for example, a modulator for an oscillation-producing device; or, more particularly, a thermionic or electronic amplifier may have its grid similarly biased as to potential, the amplifier controlling the modulator, which in turn controls the oscillation producer.

My invention resides in the further features of method and apparatus, and modifications, hereinafter described.

For an understanding of my method and for an illustration of some of the forms my apparatus may take, reference is to be had to the accompanying drawing, in which:

Fig. 1 is a diagrammatic view of radio transmitting apparatus embodying my invention.

Fig. 2 is a fragmentary diagrammatic view illustrating a modification.

Fig. 3 is a diagrammatic view of radio transmitting apparatus involving in addition to the modulator, an amplifier.

Referring to Fig. 1, V is a thermionic or electron discharge device comprising, for example, a vessel or tube evacuated to any suitable degree, as for example, and preferably, such degree as permits only of pure

electron discharge; or to lesser degree, in which case more or less gas may be present. Within the evacuated vessel are disposed the usual plate or anode *a*, cathode or filament *c*, and the grid or control electrode *g*. The cathode, particularly when a filament, as indicated, is rendered incandescent by current from any suitable source; in the example illustrated, the current is derived from the secondary *s* of a transformer whose primary *p* is connected to any suitable source of alternating current, not shown. From the substantially mid point of the secondary *s* connection is made to the conductor 1, whereby the cathode *c* is related to both the anode *a* and grid *g*. In circuit with the anode *a* is a condenser *C*, which may be of fixed capacity, or, as illustrated, may be variable, the capacity of the condenser *C* being suitable for ready passage of radio frequency currents but stopping or preventing flow of the power current supplied to the apparatus by the conductors 2 and 3. From the condenser *C* connection is made to the oscillation transformer winding or inductance *L* to which is connected also the aforesaid conductor 1, that part of the inductance between the condenser *C* and conductor 1 being preferably shunted by a condenser *C*¹, which may be fixed, or, as indicated, may be variable. The conductor 1 may be connected to earth or counterpoise capacity *E*, while the inductance *L* may be connected to the antenna *A*, an ammeter or radiation meter *W* being employed if desired. The grid *g* is connected by conductor 4 to the inductance *L* through a condenser *C*², which may be of fixed capacity, or, as indicated, may be of variable capacity, the capacity being such as to allow ready passage of currents of radio frequency. Across the grid *g* and conductor 1 may be connected a grid leak path or circuit comprising a radio frequency choke coil *d* and a resistance *R*. A source of direct current, or rectified alternating current, not shown, is connected to the conductors 2 and 3, the conductor 2 being connected to the aforesaid conductor 1 in which is the radio frequency choke coil *e*, while conductor 3 is connected through the low frequency or audio frequency choke coil *f* and thence through the radio frequency choke coil *h* with the anode *a*. Bridging the conductors 2 and 3 is a condenser *K*, preferably of capacity large

enough to smooth out the undulations or ripples in the current supplied by the source to the conductors 2 and 3. The circuit arrangements thus far described, in connection

5 with the device V, will be recognized as those suitable for producing high frequency oscillations which will be impressed upon the antenna A or upon any other circuit or system, as for example, upon the conductor 10 or conductors extending between transmitting and receiving stations in a carrier wave system.

Associated with the oscillator tube V is a second or modulator tube V¹, which is a 15 thermionic or electron discharge device, preferably a vacuum tube, the degree of vacuum being of any suitable character, such for example, as hereinbefore referred to. Its anode a¹ is connected through the 20 choke coil f with the conductor 3, and through the radio choke h with the anode a of the device V. Its cathode or filament c¹ receives current from the aforesaid transformer secondary s, or from any other suitable 25 source. The grid g¹ of the modulator tube has in its circuit the secondary s¹ of a transformer or induction coil whose primary p¹ is in circuit with the microphone or other sound-actuated controller M and a 30 source of current, as battery b.

Heretofore it has been common to connect the grid g¹ through a battery of primary or secondary cells with the conductor 1, the negative terminal of the battery being 35 connected to the grid g and the positive terminal to the conductor 1, for biasing the grid g¹, that is, for giving to it or holding it at a suitable negative potential. When so arranged, sound waves or speech uttered 40 into the microphone M causes like variation of the potential of the grid g¹, so changing the conductivity or impedance of the modulator tube V¹ and so shunting or robbing the oscillation-producing tube V to 45 cause sound wave modulation of the high frequency energy impressed upon the antenna A, for radio telephone purposes.

In accordance with my invention, however, I dispense with such grid biasing battery and connect the grid g¹ by conductor 5 with a suitable point upon the aforesaid resistance R, through which a substantial current is flowing from conductor 1 to the grid g. By this connection, particularly when 55 the voltage of the circuit 2, 3 which supplies the power is high, for example, 1000 volts when the tube V is of the so-called fifty watt capacity, a suitable lower voltage, for example, 90 or 100 volts, when the 60 tube V¹ is also of approximately 50 watt capacity, is impressed upon the grid g¹, which is so held at corresponding negative potential. While the resistance R is shown as variable, it will be understood 65 that for given circumstances it may be of

fixed value; and while the connection of the conductor 5 is shown to be variable as to its position on the resistance R, it too may be fixed at a certain suitable point.

Between the conductor 5 and the conductor 1, and to the right of the choke coil e, is a condenser K¹ of relatively large capacity, allowing easy passage of currents of low or audio frequency from the secondary s¹ to the conductor 1, but nevertheless preventing passage of direct current because of the difference of potential between conductors 5 and 1 due to passage of grid leak current through the resistance R. It shall be understood, however, that condenser K¹ 75 may be omitted, as in some cases will be found desirable.

By uttering sound waves or speech at the microphone M, the operation will be that above described, the ultimate result being 85 the variation in amplitude in accordance with sound waves or speech of the sustained high frequency energy delivered to the antenna A or other circuit or conductor.

It will be understood, therefore, that in 90 accordance with my invention the battery for biasing the grid g¹ is dispensed with, and the current in the leak circuit from the grid g is utilized for biasing the grid g¹.

In Fig. 2 a modification is shown in that 95 the resistance R of Fig. 1 is dispensed with and the conductor 5 connected to the grid g through the radio choke coil d, which, however, may be short circuited or rendered ineffective by closing the switch i, in which 100 case the conductor 5 is connected directly to the grid g.

In Fig. 3 the arrangement is similar to that of Fig. 1, except that there is provided in addition an amplifier tube V² of the 105 thermionic or electron discharge type. Its cathode c² may be supplied by current from a battery b¹ or from the same battery b in the circuit of the microphone M, which in this case is coupled by the transformer 110 p¹, s¹ to the circuit of the grid g² of the amplifier tube V². The anode a² is connected to the primary p² of a transformer whose secondary s² is in the circuit of the grid g¹ of the modulator tube V¹. The 115 transformer p², s² may be of the step-down type, though it may also be of the step-up type, according to circumstances. With the amplifier tube V² of small capacity, for example, five watts, this transformer may 120 be of the step-down type when the oscillator tube V and modulator V¹ are of larger capacity, as for example, 50 watts or more. The primary p² is connected to any suitable point upon the resistance R¹ connected at 125 one terminal to the conductor 1 and at its other terminal through the choke coil f with the conductor 3. Either or both of condensers K¹ and K² may be omitted, according 130 to circumstances.

As in Fig. 1, the grid g^1 is connected by conductor 5 to a point upon the resistance R, and between the conductors 1 and 5 is connected the condenser K¹. Similarly, the grid g^2 of the amplifier tube V² may be biased to suitable voltage, without employment of a battery, by connecting the grid g^2 by conductor 6 with a suitable point upon the resistance R, and a condenser K² connected between conductors 1 and 6, the capacity of the condenser K² being suitably large readily to pass currents of low or audio frequency.

In operation the arrangement of Fig. 3 is similar to that described in connection with Fig. 1, except that the microphone controls the amplifier V² to cause fluctuations of the current in its anode circuit in accordance with sound waves or speech, such current traversing the primary p² effecting through the secondary s² corresponding variations of the potential of the grid g^1 of the modulator tube V¹.

In this arrangement the grids of both the modulator and amplifier tubes are biased by voltages due to the current through the grid leak resistance R associated with the oscillator tube V.

It will, of course, be understood that the conductors 5 and 6 of Fig. 3 may be connected with respect to the grid g of the oscillator tube V, as indicated in Fig. 2, in which case the conductor 6 may be merely an extension of the conductor 5 or may be considered one and the same conductor connecting to both the grids g^1 and g^2 . In case it is suitable or desirable that the grids g^1 and g^2 shall be biased to or held at the same potential, the conductor 6 may connect directly to the conductor 5, and a separate and independent engagement of the contact 6 with the resistance R may be dispensed with.

As indicated in Figs. 1 and 3, the amounts of the winding or inductance L included in the antenna path, and in the grid and anode circuits of the tube V, are adjustable for determining the frequency of the oscillations produced and for procuring resonance between the different circuits and paths; and when the condensers C, C¹ and C² are variable, they too may serve for like purposes.

For determining when suitable resonance conditions exist, as when the meter W shows maximum deflection, an ammeter W¹ in the circuit of the anode a¹ of the tube V¹ may be employed, and the optimum adjustment or resonance adjustment or adjustment for maximum energy in the antenna or other conductor is determinable from the meter W¹, which under the desired circumstances shows a minimum deflection.

While, according to the foregoing description, it is my preference that the biasing of the grids g^1 and g^2 , or either of them, is wholly accomplished without recourse to a

grid biasing battery, it will be understood that the biasing electro-motive-force or electro-motive-forces procured as described by conductors 5 or 5 and 6 may be only a part of the entire biasing electro-motive-force or 70 electro-motive-forces, any other suitable source or sources of electro-motive-force being utilizable in addition, as by using a grid biasing battery or batteries connected in series with the conductor 5 or conductors 5 75 and 6 and having its or their negative terminal or terminals presented to the grid g^1 or grids g^1 and g^2 .

As to the arrangement of Fig. 1, double modulation of the high frequency oscillations 80 is believed to be effected, one, and probably the principal, modulation being that due to the change of the impedance of the modulator tube V¹ because of changes of potential of its grid g^1 as controlled by the microphone M, and the other modulation is that directly effected by variation of the potential of the grid g of the oscillator V as controlled by the microphone M.

In Fig. 3 the same situation as to double modulation of the oscillator V by the modulator V¹ is believed to obtain. In addition, however, the amplifier V² effects direct modulation of the oscillator V by change of potential of its grid g, and effects further 95 modulation of the oscillator V by robbing it by that much of the current which traverses the anode circuit of the amplifier V².

While I have herein illustrated my invention in connection with radio transmitting apparatus, it shall be understood that my invention is not limited thereto, but comprehends also radio or other receiving apparatus and any other apparatus, whether or not employed for signaling, telegraphy, 100 telephony or the like, but embodying the combinations disclosed and claimed.

For the sake of brevity in the appended claims, the term "thermionic" is employed in a generic sense to include thermionic and 110 electron discharge devices without regard or limitation to any degree of vacuum, unless otherwise expressed.

What I claim is:

1. The combination with a thermionic oscillator, of a thermionic modulator and a thermionic amplifier, each comprising an anode, grid and cathode, said amplifier controlling the potential of the grid of said modulator, and means for biasing the grid of said amplifier to a potential derived from the grid of said oscillator.

2. The combination with a thermionic oscillator, of a thermionic modulator and a thermionic amplifier, each comprising an 120 anode, grid and cathode, said amplifier controlling the potential of the grid of said modulator, means for biasing the grid of said amplifier to a potential derived from the grid of said oscillator, and means for 125 130

- 4
- biasing the grid of said modulator to a potential derived from the grid of said oscillator.
3. The combination with a thermionic oscillator comprising an anode, grid and cathode, and a grid leak path, of a thermionic modulator and a thermionic amplifier each comprising an anode, grid and cathode, said amplifier controlling the potential of the grid of said modulator, and means for biasing the grid of said amplifier to a potential derived from the grid leak path of said oscillator. 70
4. The combination with a thermionic oscillator comprising an anode, grid and cathode, and a grid leak path, of a thermionic modulator and a thermionic amplifier each comprising an anode, grid and cathode, said amplifier controlling the potential of the grid of said modulator, means for biasing the grid of said amplifier to a potential derived from the grid leak path of said oscillator, and means for biasing the grid of said modulator to a potential derived from said grid leak path of said oscillator. 75
5. The combination with a thermionic oscillator, of a thermionic modulator therefor, a thermionic amplifier controlling said modulator, an impedance connected in parallel with the anode circuit of said modulator, and a connection from the anode circuit of said amplifier to said impedance, whereby the anode circuit of said amplifier has impressed thereon a lesser voltage than that impressed upon the anode circuit of said modulator. 80
6. The combination with a thermionic oscillator, of a thermionic modulator therefor, a thermionic amplifier controlling said modulator, a resistance connected in parallel with the anode circuit of said modulator, and a connection from the anode circuit of said amplifier to said resistance, whereby the anode circuit of said amplifier has impressed thereon a lesser voltage than that impressed upon the anode circuit of said modulator. 85
7. The combination with a thermionic oscillator, of a thermionic modulator therefor, a thermionic amplifier controlling said modulator, an impedance connected in parallel with the anode circuit of said modulator, a connection from the anode circuit of said amplifier to said impedance, whereby the anode circuit of said amplifier has impressed thereon a lesser voltage than that impressed upon the anode circuit of said modulator, and a source of current common to the anode circuits of said oscillator and modulator. 90
8. The combination with a thermionic oscillator, of a thermionic modulator therefor, a thermionic amplifier controlling said modulator, a resistance connected in parallel with the anode circuit of said modulator, a connection from the anode circuit of said amplifier to said resistance, whereby the anode circuit of said amplifier has impressed thereon a lesser voltage than that impressed upon the anode circuit of said modulator, and a source of current common to the anode circuits of said oscillator and modulator. 95
9. The combination with a thermionic device comprising anode, grid and cathode, of a second thermionic device comprising anode, grid and cathode, means for biasing the grid of said second device to a potential derived from the grid of said first named device, means for changing the potential of the grid of said second device, and a condenser traversed by currents of low or audio frequency connected in series between the grid and the cathode of said second device. 100
10. The combination with a thermionic device comprising anode, grid and cathode, of a second thermionic device comprising anode, grid and cathode, means for biasing the grid of said second device to a potential derived from the grid of said first named device, and a condenser traversed by currents of low or audio frequency connected in series between the grids and cathodes of said devices. 105
11. The combination with a thermionic oscillator, of a thermionic modulator therefor, a thermionic amplifier, each having an anode, grid and cathode, means for biasing the grids of said modulator and amplifier as to their potentials by derivation from the grid of said oscillator, means for changing the potential of the grid of said modulator, a condenser connected between said means and the cathode of said modulator, means for changing the potential of the grid of said amplifier, and a condenser connected between said last named means and the cathode of said amplifier. 110
12. The combination with a thermionic oscillator, of a thermionic modulator, each comprising an anode, grid and cathode, the anode circuits of said oscillator and modulator being included in parallel paths, a single source of energy for said anode circuits, means for changing the potential of the grids of said oscillator and modulator in opposite senses, a thermionic amplifier comprising an anode, grid and cathode, and means for changing the potential of the grids of said amplifier and said oscillator in opposite senses. 115
13. The combination with a thermionic oscillator, of a thermionic modulator, a thermionic amplifier, each comprising an anode, grid and cathode, the anode circuits of said oscillator and modulator being included in parallel paths, a single source of energy for said anode circuits, means for biasing the grids of said modulator and amplifier to potentials derived from the grid of said oscillator, and means for changing the potential of the grids of said oscillator and amplifier in opposite senses. 120
14. The combination with a thermionic oscillator, of a thermionic modulator, a thermionic amplifier, each comprising an anode, grid and cathode, the anode circuits of said oscillator and modulator being included in parallel paths, a single source of energy for said anode circuits, means for biasing the grids of said modulator and amplifier to potentials derived from the grid of said oscillator, and means for changing the potential of the grids of said oscillator and amplifier in opposite senses. 125
15. The combination with a thermionic oscillator, of a thermionic modulator, a thermionic amplifier, each comprising an anode, grid and cathode, the anode circuits of said oscillator and modulator being included in parallel paths, a single source of energy for said anode circuits, means for biasing the grids of said modulator and amplifier to potentials derived from the grid of said oscillator, and means for changing the potential of the grids of said oscillator and amplifier in opposite senses. 130

14. The combination with a thermionic oscillator, of a thermionic modulator, a thermionic amplifier, each having an anode, grid and cathode, the anode circuits of said oscillator, modulator and amplifier being connected in parallel paths, a source of current common to said anode circuits, and means for changing the potentials of the grids of said amplifier and modulator in the same sense and the potential of the grid of said oscillator in opposite-sense. 10
15. The combination with a thermionic oscillator, of a thermionic modulator, said oscillator having a grid leak containing a resistance, a connection from said resistance to the grid of said modulator, means for controlling the potential of the grid of said modulator in accordance with sound waves, and a condenser connected across a portion 20 of said resistance and having a capacity suitable for passing current of sound wave frequencies. 15
16. The combination with a thermionic oscillator comprising a thermionic device having an anode, grid and cathode, a coupling between the grid and anode circuits, a condenser in the connection between the grid and the coupling, a second thermionic device having anode grid and cathode, and a connection from a point between said condenser and the grid of said first named thermionic device to the grid of said second thermionic device. 25
17. The combination with a thermionic oscillator, of a thermionic modulator and a thermionic amplifier, each comprising an anode, grid and cathode, said amplifier controlling the potential of the grid of said modulator, and means for biasing the grid 30 of said amplifier to a potential derived from the grid of said oscillator. 5
18. The combination with a thermionic oscillator, of a thermionic modulator and a thermionic amplifier, each comprising an anode, grid and cathode, said amplifier controlling the potential of the grid of said modulator, the grid of said oscillator having a leak path, and means for biasing the grid of said amplifier to a potential derived from said leak path. 10
19. The combination with a thermionic oscillator, of a thermionic modulator and a thermionic amplifier, each comprising an anode, grid and cathode, said amplifier controlling the potential of the grid of said modulator, and means for influencing the potential of the grid of said modulator and the potential of the grid of said amplifier by the grid of said oscillator. 15
20. The combination with a thermionic oscillator, of a thermionic modulator and a thermionic amplifier, each comprising an anode, grid and cathode, said amplifier controlling the potential of the grid of said modulator, the grid of said oscillator having a leak path, and means for influencing the potential of the grid of said modulator and the potential of the grid of said amplifier by the grid of said oscillator. 20
21. The combination with a thermionic oscillator, of a thermionic modulator and a thermionic amplifier, each comprising an anode, grid and cathode, the anode circuits of said oscillator and modulator being included in parallel paths, a common source of energy for said anode circuits, the anode circuit of said amplifier controlling the potential of the grid of said modulator, and means for biasing the grid of said amplifier to a potential derived from the grid of said oscillator. 70
22. The combination with a thermionic oscillator, of a thermionic modulator and a thermionic amplifier, each comprising an anode, grid and cathode, the anode circuits of said oscillator and modulator being included in parallel paths, a common source of energy for said anode circuits, the anode circuit of said amplifier controlling the potential of the grid of said modulator, and means for influencing the potential of the grid of said modulator and the potential of the grid of said amplifier by the grid of said oscillator. 80
23. The combination with a thermionic oscillator, of a thermionic modulator and a thermionic amplifier, each comprising an anode, grid and cathode, the anode circuits of said oscillator and modulator being included in parallel paths, a common source of energy for said anode circuits, the anode circuit of said amplifier controlling the potential of the grid of said modulator, a leak path for the grid of said oscillator, and means for biasing the grid of said amplifier to a potential derived from said leak path. 90
24. The combination with a thermionic oscillator, of a thermionic modulator and a thermionic amplifier, each comprising an anode, grid and cathode, the anode circuits of said oscillator and modulator being included in parallel paths, a common source of energy for said anode circuits, the anode circuit of said amplifier controlling the potential of the grid of said modulator, a leak path for the grid of said oscillator, and means for influencing the potential of the grid of said modulator and the potential of the grid of said amplifier by said leak path. 100
25. The combination with a thermionic oscillator, of a thermionic modulator and a thermionic amplifier, each comprising an anode, grid and cathode, said modulator controlling the production of oscillations by said oscillator, said amplifier controlling the potential of the grid of said modulator, and means for biasing the grids of said modulator and amplifier to different potentials from the grid of said oscillator. 110
26. The combination with a thermionic os- 120
- 125
- 130

cillator, of a thermionic modulator and a thermionic amplifier, each comprising an anode, grid and cathode, said modulator controlling the production of oscillations 5 by said oscillator, said amplifier controlling the potential of the grid of said modulator, an impedance connected to the grid of said oscillator, and connections from different points on said impedance to the grids of said 10 modulator and amplifier.

27. The combination with a thermionic oscillator comprising an anode, cathode and

grid, of means for coupling the anode and grid circuits for producing oscillations, a path from grid to cathode including an inductively reactive impedance independent of 15 said coupling, a second thermionic device comprising an anode, cathode and grid, and a connection from said path to the grid of said second device for influencing the potential thereof.

In testimony whereof I have hereunto affixed my signature this 1st day of July, 1921.

THOMAS APPLEBY.
